SMOKESTACK AND FLUE-PIPE ADAPTER

Frank F. Lalande, Challis, Idaho

Application May 8, 1944, Serial No. 534,626

2 Claims. (Cl. 126—314)

This invention relates to a novel and improved flue adapter designed to fit in a stack accommodation collar, said adapter being shaped and fashioned to accommodate a coacting end of the stove pipe or flue and being such as to provide a "clean-out" for soot and dirt.

In accordance with the principles of this invention and in fulfilling my aims, I have devised a special fitting for a smokestack, which fitting is unitarily referred to as an adapter, the same having a nipple to slip into an accommodation collar in the stack and a projecting scoop-like extension functioning as a satisfactory union for the flue and also as a spout into and from which the soot may be scraped into a bucket or the like.

In carrying out the ideas of the invention when reducing the same to physical and practical form, I have perfected a simple and economical adapter attachment which is aptly suited for the purposes intended and which is provided with a keeper hook to accommodate a latch on the flue-pipe and which also serves as a hanger for the bail on the soot-collecting bucket.

Other features and advantages will become more readily apparent from the following description and the accompanying illustrative drawing.

In the drawing, wherein like numerals are employed to designate like parts throughout the same—

Figure 1 is a view partly in section and partly in elevation showing a portion of the smokestack, the flue-pipe from the stove or other equipment and the special adapter fitting which serves as a union between the smokestack and flue.

Figure 2 is a view similar to Figure 1, the parts being in section, the flue removed and there being a bucket shown for conveniently trapping the sediment and soot.

Figure 3 is a fragmentary sectional view of the reducing thimble on the stove pipe or flue.

Figure 4 is a perspective view of the adapter per se showing the overall construction.

The adapter, which is in the form of a fitting or attachment, is denoted by the numeral 5 and is of appropriate material and dimensions and is characterized by a cylindrical nipple or sleeve 6, terminating in circumferentially spaced outstanding bendable fingers 7. This part is of smaller diameter than the extending end portion 8 and a shoulder is thus defined between the two parts. The extending portion has its upper half cut away with the walls cut down on opposed compound curved lines to define a scoop-like spout 9. The nipple 6 slips into the accommoda-

tion collar or bushing 10 mounted in the vent in the coacting wall of the stack 11. The prongs or tongues 7 are bent laterally to thus hold the parts assembled. The flue or stove pipe is indicated at 12 and has a reduced thimble 13 which slips up into the nipple telescopically in an evident manner. It will be noticed in Figure 1 that a pivoted keeper latch 14 is provided on the bottom half of the flue and the bill thereof is adapted to engage with a keeper hook 15 on the lower central portion of the tip of the spout. The keeper hook serves to maintain the parts assembled in telescopic relation as shown in Figure 1. It also serves as a hanger for the bail 16 of the soot collecting bucket 17 as shown in Figure 2. The scoop-like shape of the extension of the adapter provides accessibility and facilitates coupling and uncoupling of the flue pipe 12.

In practice, it is evident that the adapter 5 is anchored in the collar and held in place by the bendable prongs or tongues 7 and the extension provides a saddle for properly seating the coacting end portion of the stove pipe 12. The thimble 13 projects into the nipple and the shoulders on the respective parts coact in abutting relationship to assist in maintaining the parts assembled. Then they are latched securely together and properly coupled as shown in Figure 1. When the latch is detached the pipe 12 can be slipped out to expose the scoop-like spout extension 9. The latter serves as a convenient suspension or hanger means for the bucket 17 and also, its top portion being cut away, facilitates scraping of the dirt and soot by a suitable device (not shown) into the bucket.

The device is simple and expedient, foolproof, reliable and otherwise susceptible of achieving the desired aims.

It is thought that persons skilled in the art to which the invention relates will be able to obtain a clear understanding of the invention after considering the description in connection with the drawing. Therefore, a more lengthy description is regarded as unnecessary.

Minor changes in the shape, size and arrangement of details coming within the field of invention claimed may be resorted to in actual practice, if desired.

Having described the invention, what is claimed as new is:

1. In a smokestack and flue pipe adapter, a pipe section having a reduced end adapted to fit a flue thimble said end having integral bendable fingers adapted to engage the inner edge of the thimble, a shoulder on said section adapted to

engage the outer edge of said thimble whereby the section is held against movement, said section also including a cylindrical portion beyond said shoulder, and a semi-cylindrical stovepipe holding extension projecting from said cylindrical portion.

2. In a smokestack and flue adapter, a one-piece pipe section having at one end a reduced nipple portion of predetermined length and diameter to snugly fit in a conventional flue thimble,

also having spaced integral abutment elements at opposite end portions thereof, these for securely fastening said nipple portion within said thimble, said section also including a cylindrical portion projecting beyond the adjacent abutment element, and a semi-cylindrical stovepipe holding extension projecting from said cylindrical portion.

FRANK F. LALANDE.
